[57] CLAIM

The ornamental design for a combined vehicle door
opener and key inserter, as shown and described.

DESCRIPTION

FIG. 1 is a front and left side perspective view of the
combined vehicle door opener and key inserter showing
my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof.

The key is shown in broken lines in FIGS. 1 and 4 for
illustrative purposes only and forms no part of the
claimed design.
